(57) **CLAIM**

The ornamental design for a bandage, as shown and
described.

DESCRIPTION

FIG. 1 is a bottom top of a bandage of our design.

FIG. 2 is a first side view of the bandage of FIG. 1.

FIG. 3 is a second side view of the bandage of FIG. 1.

FIG. 4 is a top bottom of the bandage of FIG. 1.

FIG. 5 is a third side view of the bandage of FIG. 1; and,

FIG. 6 is a fourth side view of the bandage of FIG. 1.

The broken lines shown in the figures are included for the
purpose of illustrating portions of the surgical tool and form
no part of the claimed design. Randomly dashed lines
represent surface shading.
